FITTED SUIT CASE CONSTRUCTION

Filed May 29, 1930 2 Sheets-Sheet 2

Inventor
ALBERT H. LAST,

J. F. Bassiches
his attorney

UNITED STATES PATENT OFFICE

ALBERT H. LAST, OF NEW YORK, N. Y.

FITTED SUITCASE CONSTRUCTION

Application filed May 29, 1930. Serial No. 457,025.

This invention relates to luggage; more particularly, hand luggage, such as suitcases.

It is an object of my invention to provide hand luggage, such as a suitcase, including fittings, and equivalent articles of toiletries, as may be conveniently carried within the suitcase, and assemble the same with one of the elements comprising the suitcase, such as the cover, so that when the suitcase is opened, the body of the suitcase will support the cover and the cover, in turn, will support the fittings and equivalent articles of toiletries, to make the fittings easily accessible to the user.

It is contemplated by my invention to combine with a suitcase, fittings including articles of toiletries, which may be conveniently carried in a suitcase and which, when so carried, will not in any way interfere with the apparel stored in the suitcase, so that during transportation, fittings will not be dislodged upon the articles of clothing carried in the suitcase, preventing soiling of the clothing.

It is further contemplated as an object of my invention to provide a suitcase which includes in the cover member, mountings for fittings, and associating with the cover member, interiorly thereof, a shield or closure, to thereby form, with the cover, a separate and independent compartment whereby the fittings carried by said mountings will, during transportation, if dislodged, avoid contact with the articles of apparel carried in the suitcase, to maintain both the articles of apparel and the fittings unsmeared due to contact with each other.

A still further object of my invention resides in the provision of hand luggage, such as a suitcase, which has provided in one of the elements thereof, such as the cover member, mountings for articles of toiletries, to have them conveniently accessible when the suitcase is opened, and to enclose the same in a separate and independent compartment, characterized by providing interiorly of said cover member, a shield or closure, and further characterized by simple and convenient structural mounting for the shield or cover to additionally provide within the suitcase, mountings for articles of apparel, such as pouches or pockets and thereby increase the

capacity of the suitcase for storage and packing purposes.

To attain these objects and such further objects as may appear herein or be herein-after pointed out, I make reference to the accompanying drawing, forming a part thereof, in which—

Figure 1 is a perspective view of my device as embodied in a suitcase, with the suitcase opened;

Figure 2 is a section taken on the line 2—2 of Figure 1;

Figure 3 is a front elevation of the cover member, with the fitting compartment closures in the open position;

Figure 4 is a section taken on the line 4—4 of Figure 2.

Making reference to the drawing, in my preferred embodiment, I associate my invention in connection with a suitcase 10. In this construction, the body member 11 is of the character which has a closure or cover 12, hingedly mounted thereto, and arranged to be maintained in an erect or vertical position, when the body member lies flat upon some surface, such as a table, or chair, or the like, and is prevented from falling backwards by straps 13.

In this construction, also, locking members, such as 14, serve to maintain the body member and cover member in locked relationship for shipment.

Preferably, within the cover member, in the side wall 15, there is provided a plurality of fitting mountings 16, for holding such articles of toiletries, such as combs, hair brushes, nail files, mirrors, buffers and the like. These fitting mountings, of the well known character, include straps affixed to the wall, preferably including snap fastener connection to permit the articles of toiletries to be conveniently removed.

As this method of mounting fittings or articles of toiletries does not form part of my invention, no more detailed description will be made. However, it is contemplated by me to avoid the annoyance of having these fittings or articles of toiletries accidentally become dislodged and come in contact with the clothing carried in the suitcase. I there-

fore convert the cover member into an independent compartment, and this I accomplish by disposing a pair of hinged closure members 17 and 18, including fastening elements 19, in the nature of straps, including complementary snap fasteners 20, to maintain the fitting mountings and fittings carried thereby confined within a separate compartment.

The closures 17 and 18 may be disposed from the edge walls 21 and 22 of the suitcase. Preferably, however, I dispose intermediate walls 21' and 22', dividing the cover member into three independent compartments, 23, 24 and 25. From the edges 26 and 27 of the walls 21' and 22', respectively, the closures 17 and 18 are preferably mounted by a hinge construction. This hinge is formed by extending the covering fabric from the closures to the walls, the flexibility 20 of the fabric serving as the hinge.

Disposed interiorly of the compartment 24, and affixed to the walls 21' and 22', respectively, I provide hinged spring fingers 28. These include an operating section 29, pivotally mounted to the plate 30, and including a coiled spring 31, to urge the section 29 outwardly. The section 29 is provided with a camming edge 32 and this edge thereby contacts with the interior wall of the closures 17 and 18 so that upon release of the snap fasteners 20, engaging the closures 17 and 18 with each other, they will immediately be urged to the open position, as illustrated in Figure 3.

35 Inward hinged movement of the closures 17 and 18 is prevented by providing abutting ridges 26a and 27a at the top and bottom edges, respectively, of the cover member 12.

Upon the interior face of the closures 17 and 18', I may provide additional fitting mountings 17a and 18a, arranged to hold a mirror 17b and 18b thereon. It will be observed that these mirrors may be removable and the fitting mountings, particularly those disposed near the top corners, may be released by snap fastener elements, as shown.

By this construction, the closures 17 and 18 provided do not merely serve to form an independent or separate compartment for the fittings or articles of toiletries retained within the compartment 24, but may be conveniently used, additionally, for in themselves supporting additional articles of toiletries and to thereby enlarge the capacity for retaining these articles.

Additionally, also, the interior face of the closures 17 and 18 may have affixed thereto pockets 17c and 18c, provided with elastic edges 17d and 18d, to make the exterior face 60 of the closures available for additional storage space. Thus, by the construction provided, I increase the capacity of the cover member for storage space, in no way defeated by supplying the suitcase with the fittings 65 and fitting mountings on the cover member

12. Additionally, also, within the compartments 23 and 25 I may provide pouches or pockets 23a and 25a, respectively, including elastic edges 23b and 25b, forming a closure for these pockets.

It will be additionally observed that when the suitcase is mounted in position, the body member 11 serves as a base for the lid 12 in the vertical position of the latter, and that when the closures 17 and 18 are outwardly hinged to the position shown in Figure 2 by the dotted lines, particularly overlapping the edge, the lid is held against accidental downward movement to the closed position thereof. Thus, the closures 17 and 18, when mounted in position as described, serve in the nature of hinge stops to hold the lid and the fittings carried thereby, particularly the mirrors, in a vertical position.

By the construction illustrated and described, it will be observed that an ordinary suitcase may have provided on the interior face of the cover member, fitting mountings for holding fittings and equivalent articles of toiletries, to provide a sanitary construction for the fittings and for the articles of apparel carried in the suitcase, by avoiding contact of these articles with each other, as may result from accidental dislodgement of the fittings.

It will thus be observed that I have not only provided the novel construction above described but have additionally increased the capacity of the suitcase by providing additional storage space and compartments resulting from this construction.

It will further be observed that the fittings carried within the fitting compartment are protected against breakage caused by any loose articles carried within the suitcase, due to tumbling during transportation and also, by reason of the closure member provided and the construction described, they are prevented from being pressed against articles which may be carried inside the suitcase during storage of the suitcase, as when the same is stacked in any way.

Having thus described my invention and illustrated its use, what I claim as new and desire to secure by Letters Patent, is—

1. A suit case including fittings, comprising a bottom member serving as a base from which the lid thereof extends substantially perpendicularly when open, partitions within the lid outlining a compartment for said fittings and including in said compartment fitting mountings, laterally hinged closure members carried by said partitions formed to pivot outwardly over the bottom member to a position rendering the contents of the bottom member freely accessible and to move to a position overlapping an edge wall of the bottom member, to prevent accidental closure of the lid.

2. A suitcase including fittings comprising

a bottom member and a lid therefor, the bottom member serving as a base from which the lid thereof extends substantially perpendicularly when open, fitting mountings for said fittings carried by said lid, accessible interiorly of said lid, a pair of partition members carried by said lid outlining a separate compartment for said fittings, closures carried by said partition members, means for urging said closures to the open position laterally in overlapping position over the upper edge of the side of the bottom member of said suitcase when said lid is substantially in the vertical position whereby the lid is held against accidental movement to the closed position.

3. A suitcase, comprising a lid member and a bottom member serving as a base from which the lid extends perpendicularly when open, a pair of spaced laterally hinged closures carried by partitioning means in said lid, and foldable inwardly of said lid in closed position into substantially coterminous contact, complementary fastening means carried by said closures, said closures being pivotable laterally and outwardly to the open position into overlapping position over an edge wall of the bottom member.

In witness whereof I have hereunto signed
30 my name this 20th day of May, 1930.

ALBERT H. LAST.
